DIAPER WASHING APPARATUS

James W. Sampson and Charles Mervin
Champion, Sheridan, Wyo.

Application August 16, 1949, Serial No. 110,486

1 Claim. (Cl. 68—245)

1

The present invention relates to washing apparatus, and more particularly to apparatus for the washing and partial drying of small articles of apparel, such as diapers.

Since time immemorial the problem of cleansing or washing diapers and similar children's garments has plagued mankind. The long-felt and widespread need for a simple, inexpensive, easily operated washing apparatus for this purpose will be evident.

The present invention now provides washing apparatus for this purpose and obviates the necessity of performing the disagreeable and unsanitary task of manually cleansing diapers and the like.

The apparatus of the present invention includes a backing plate having a substantially plane upper washing surface and opposed upturned marginal flanges, the entire washing surface and the integrally formed flanges providing a smooth sanitary washing surface upon which debris will not accumulate. Means are also provided for retaining an article to be washed in position upon the washing surface, as well as means for removing excessive moisture from the article following washing. These means desirably take the form of a single wringer roll which is journaled between the opposing marginal flanges of the washing surface. The roll is urged toward the washing surface by suitable means to retain an article to be washed in position between the washing surface and the roll.

Preferably, the roll is journaled within inclined slots formed in the washing surface flanges, so that to wring the clothes it is merely necessary to pull the washed article from its position between the washing surface and the roller. The force which is applied to so remove the washed article is at least partially resolved into a vertical component by reason of movement of the roll within the inclined slots. The vertical component of force thus applied to the roll urges the roll toward the washing surface, and frictional contact between the washed article and the roll causes rotation of the roll to effectively wring excessive moisture from the washed article.

It is, therefore, an important object of the present invention to provide an improved, inexpensive, easily employed washing apparatus.

It is another important object of the present invention to provide an improved washing apparatus in which an article to be washed is maintained in contact with a washing surface by means of a wringer roll.

A further important object of the present in-

2

vention is to provide an improved washing apparatus in which excessive moisture is removed from a washed article interposed between a washing surface and a wringer roll by merely pulling the article from its interposed position.

Still another important object of the present invention is to provide washing apparatus in which excessive moisture is removed from a washed article positioned upon a washing surface and interposed between the surface and a wringer roll by merely pulling the article from its interposed position in frictional contact with the wringer roll, the force exerted in so removing the washed article serving to urge the wringer article to effectively remove moisture therefrom.

Other and further important objects of this invention will be apparent from the disclosures in the specification and the accompanying drawings.

On the drawings:

Figure 1 is a side elevational view, with parts broken away, showing the positioning of washing apparatus of the present invention within a toilet bowl or the like;

Figure 2 is a plan elevational view of washing apparatus of the present invention showing an article to be washed positioned therein; and

Figure 3 is a sectional view taken along the plane III—III of Figure 2.

As shown on the drawings:

In Figure 1, reference numeral 10 refers generally to washing apparatus of the present invention positioned within a toilet bowl 11.

As best shown on Figures 2 and 3, the washing apparatus of the present invention comprises a backing plate 12 having a substantially plane upper washing surface and opposed integrally formed, upstanding marginal side walls 13 extending substantially normal to the plane of the washing surface of the backing plate 12. A handle 14 extends between the flanges 13 substantially parallel to the plane of the backing plate 12, the handle 14 being provided with terminal downturned ears 15 secured to the flanges by suitable means, as by rivets 16.

Each of the flanges 13 is provided with an elongated, inclined slot 17 adjacent to one edge thereof, and a wringer roll 18 formed of suitable material, such as rubber, plastic, wood, metal, or the like, is journaled in the slots 17. Each end face of the roll 18 carries a stub shaft 19 fixedly secured therein and extending through each of the slots 17, each of the stub shafts 19 having an

enlarged head 20 outside the flange 13 to prevent displacement of the roll 18.

The roll 18 is urged toward the upper plane surface of the backing plate 12 by means of a pair of coil springs 21, each of which is secured at one end to one of the flanges 13 adjacent one end thereof, as by rivets 22. The free end of each of the springs 21 is secured to the adjacent stub shaft 19. It will thus be seen that the springs 21 urge the roll 18 downwardly within the slot 17 toward the backing plate 12.

The operation of the device of the present invention will be evident from the drawings. A diaper D or similar article to be washed is positioned within the apparatus in generally flatwise contact with the upper plane surface of the backing plate 12, the article D being secured in position by being interposed between the backing plate 12 and the roll 18. Next, the apparatus 10 is positioned within means for providing drainage for water or other washing medium introduced onto the article D, preferably within a toilet bowl 11, as shown in Figure 1. Water is next introduced onto the article D by suitable means, as from nozzle N shown in Figure 1.

Following the rinsing or washing of the article D, excessive moisture is wrung from the article by merely pulling the same in a plane substantially coincident with that of the backing plate 12 to pass the article D between the roll 18 and the backing surface. It will be readily understood that the force required to remove the article will be slight inasmuch as the backing surface 12 is substantially plane. However, such force as is required will be at least partially resolved into a force exerted vertically on the roll 18 since the roll is journaled within the inclined slots 17. The vertical component of the force employed to remove the article D, in conjunction with the force exerted upon the roll 18 by the springs 21, will cause tight frictional engagement between the roll and the article D, so that excessive moisture is effectively wrung from the article during its removal from the apparatus.

The advantages residing in the present invention will be immediately evident to those skilled in the art. First, the plane upper surface of the backing plate 12 and the upturned flanges 13 present no interference to the ready washing of

debris from the article D. Thus, the apparatus is sanitary in use and readily employed. Second, the roll 18 is urged against the backing plate 12 by means of the springs 21 and thus serves to retain an article to be washed in position upon the backing plate 12. Third, the device 10 effectively removes excessive moisture from the article D by means of the roll 18. Fourth, the roll 18 is urged against the backing plate 12 both by the springs 21 and by the force required to remove the article D from its position upon the backing plate 12, thus insuring efficient moisture removal.

It will also be apparent that various modifications may be made without departing from the novel concept herein presented. For example, the springs 21 may be made of sufficient strength so that it is not necessary to employ the inclined slots 17. Also, sufficient wringing action may be obtained by relying solely upon the force exerted upon the roller during removal of the article D to wring the article, thus making possible the elimination of the springs 21. Further, the flanges 13 may be formed separately from the backing plate 12 and secured thereto by suitable means, as by welding, brazing, or the like.

It will be understood that modifications and variations may be effected without departing from the scope of the novel concepts of the present invention.

We claim as our invention:

In washing apparatus, a board, upstanding flange means disposed on opposite sides of said board and having aligned slots adjacent one end of said board and inclined toward said board and toward said one end thereof, a wringer roll journaled for rotation in said slots, and means to resiliently urge said wringer roll toward said board.

JAMES W. SAMPSON.

CHARLES MERVIN CHAMPION.
